CLAIM

The ornamental design for a wheeled tool box, as shown and described.

DESCRIPTION

FIG. 1 is a rear perspective view of our new design with the handle extended.

FIG. 2 is front perspective view.

FIG. 3 is a front view thereof.

FIG. 4 is a back view thereof.

FIG. 5 is a right side view thereof.

FIG. 6 is a left side view thereof.

FIG. 7 is a bottom view thereof.

FIG. 8 is a top view thereof.

FIG. 9 is a rear perspective view with the handle retracted.

FIG. 10 is front perspective view.

FIG. 11 is a front view thereof.

FIG. 12 is a back side view thereof.

FIG. 13 is a right side view thereof.

FIG. 14 is a left side view thereof.

FIG. 15 is a bottom view thereof; and,

FIG. 16 is a top view thereof.

The broken lines illustrated portions of the wheeled tool box and form no part of the claimed design.

1 Claim, 16 Drawing Sheets
